UNITED STATES PATENT OFFICE.

SAMUEL J. SPALDING, OF CANTON, OHIO.

ELECTROGALVANIC BELT.

SPECIFICATION forming part of Letters Patent No. 551,795, dated December 24, 1895.

Application filed May 9, 1895. Serial No. 548,650. (No model.)

To all whom it may concern:

Be it known that I, SAMUEL J. SPALDING, a citizen of the United States, residing at Canton, in the county of Stark and State of Ohio, have invented certain new and useful Improvements in Electrogalvanic Belts; and I do hereby declare that the following is a full, clear, and exact description of the same, reference being had to the annexed drawings, making a part of this specification, and to the letters of reference marked thereon, in which—

Figure 1 is a view showing the belt properly located upon the body, also showing the suspensory properly connected. Fig. 2 is a view showing a portion of the belt-casing, also showing cell connection to the electrode. Fig. 3 is a transverse section of one of the cells, showing the location of the pad with reference to the plates. Fig. 4 is a detached view of one of the cells. Fig. 5 is a longitudinal section showing a number of cells properly hinged together. Fig. 6 is a view showing the belt opened and illustrating the different cells and elastic connections properly arranged. Fig. 7 is a view showing the cell-connection link insulated and illustrating a detachable electrode properly connected. Fig. 8 is a detached view of the hinge for connecting the cells.

The present invention has relation to electrogalvanic belts; and it consists in the different parts and combination of parts hereinafter described, and particularly pointed out in the claims.

Similar letters of reference indicate corresponding parts in all figures of the drawings.

In the accompanying drawings, A represents the casing or cover, which is constructed in the ordinary manner, reference being had to properly attaching and adjusting the different parts of the belt proper, said cover being folded so as to properly inclose the cells and their different attachments. The cover or sheath is provided with any desired number of electrodes, such as *a*, which electrodes may be located as shown, one of the electrodes *a* being provided with the hook *b*, which hook is for the purpose of connecting the elastic connection *B* to one of the end cells by means of the links *c* and *d*, said links

being located and arranged substantially as shown in Fig. 6.

When it is desired to provide a belt with four electrodes, as shown in Fig. 6, the center elastic connections *C* are provided, which are located substantially as illustrated in Fig. 6, and the ends of said connections provided with the clamps *d'*, which clamps are for the purpose of engaging the links *d²*, thereby properly connecting the two systems of cells, and at the same time holding the cells in proper position within the case or covering.

To one of the electrodes *a* is connected the hook *D*, to which hook is attached the reversible link *D'*, said reversible link being journaled or pivotally connected to the link *D²* by means of suitable eyes *a'* or their equivalents. For the purpose of providing a means for insulating the electrodes *a*, to which the reversible link *D'* is attached, one end of said reversible link is provided with suitable insulating material, as illustrated in Figs. 6 and 7. The object and purpose of insulating one end of the reversible link *D'* is to provide a means for increasing and decreasing the battery power by cutting in or out the cells, as hereinafter described.

The battery-cells consist of the zinc plates *a²* and the copper plates *a³*, which plates are located with reference to each other substantially as shown in the drawings, and the felt *a⁴*, all of said parts being properly bound together by means of suitable cords *a⁵*.

For the purpose of providing an elastic connection for each side of the different cells said cells are independently connected together by means of the wires *b'*, one branch of said wire *b'* being connected to the zinc plates *a²* and the other branch being connected to the copper plates *a³*, and the two wires *b'* connected together between the cells by means of the coil *b²*, said coil being formed with the longitudinal opening *b³*, said opening being of sufficient size to receive and connect the wires *b'*, and at the same time receive the plug *E*, as illustrated in Fig. 7, said plug *E* being properly connected to the insulated wire *F*, said insulated wire being connected to the eye *f*, said eye being properly connected to the proper electrodes *a*.

When it is desired to reduce the strength of

the batteries proper, the plug E is removed from the reversible hook or link D' to include the desired number of cells, thereby cutting out the cells located between the plug E and the hook D, the strength of the belt proper being governed by the number of cells cut out.

When it is desired to use the full force of the belt-batteries, the plug E is removed and the reversible link D' turned so as to connect the uninsulated portion of said reversible link with the hook D.

For the purpose of providing a means for carrying the current to any desired part of the body—say to the wrist or arm—the electrode 15 G is provided, which electrode is provided with a suitable attaching-clamp or binding-strap, such as H, and the proper connection made by means of the wire g and the hook g'.

It will be understood that when the electrode G is connected as illustrated in Fig. 7, said electrode becomes active, or, in other words, is located at the end of the circuit.

For the purpose of providing cells that will retain the exciting-fluid for a considerable 25 length of time, the plates a^2 and a^3 are convexo-concave both longitudinally and transversely, thereby providing plates that will bind or press the felt a^4 only at the ends and sides of the felt, thus leaving the central portion 30 uncompressed, and yet at the same time allowing the felt to come into proper contact with the zinc and copper plates.

For the purpose of providing a means for adjusting the suspensory I longitudinally 35 upon the belt proper independent of the electrode, said suspensory is provided with the strap J, to which strap is attached the clasp K, which clasp can be moved to any desired point of the sheath and quickly connected 40 thereto.

For the purpose of providing a means for vertically adjusting the suspensory, the strap J is provided with a suitable buckle, such as k or its equivalent.

45 The object and purpose of providing for lateral adjustment of the suspensory I is to bring suspensory in proper position independent of the position of the belt proper, thereby providing a means for adjusting the electrode a 50 upon the body without any reference to the position of the suspensory, the current being conveyed to the suspensory by means of the wire k' and its hook k², said hook being properly connected to the eye f, as illustrated in 55 Fig. 1.

It will be understood that the suspensory I may be insulated, if desired, thereby preventing any injury by reason of a heavy current.

If desired the cells may be provided with 60 the eyes h, which eyes are properly connected to one of the plates a^2 or a^3 , as desired, said eyes being for the purpose of receiving the

hook h', said hook being for the purpose of making connection to one of the electrodes a by means of the wire h².

65 Heretofore it has been customary to form the felt a^4 of different layers of material, so as to produce a felt of sufficient thickness; but I prefer to use a thick felt known as "fawn's hair," the felt being formed of a 70 thickness to correspond with the thickness of the felt proper. By using felt of this material the exciting-fluid will be retained much longer, thereby producing better results, and at the same time producing a battery of 75 greater power.

Having fully described my invention, what I claim as new, and desire to secure by Letters Patent, is—

1. In an electro-galvanic belt, the combination of a sheath, having connected thereto a series of cells by means of the elastic connection B, the reversible link D', one end thereof provided with insulating material and a number of electrodes secured to the sheath, and a 80 hook as D, substantially as and for the purpose specified.

2. In an electro-galvanic belt, the convexo-concave plates a^2 and a^3 , the wires b' connected to the convexo-concave plates, the coil 90 b² surrounding the wires b' and the felt a⁴ formed of fawn hair, and of a single thickness, substantially as and for the purpose specified.

3. The combination of the cells consisting 95 of the convexo-concave plates a^2 and a^3 , connected together, the felt a⁴, located between the plates and clamped at the ends and sides of said felt upon opposite sides thereof, substantially as and for the purpose specified. 100

4. The combination of the cells with their hinges formed of the coils b² and wires b', and the plug adapted for insertion into the coils of the hinges, substantially as and for the purpose specified. 105

5. In an electro-galvanic belt a sheath, provided with a series of cells, the suspensory I attached to the sheath, so as to be vertically and longitudinally adjustable independent of the electrodes, the wire k' provided with the hook k², and the eye f, substantially as and for the purpose specified. 110

6. In an electro-galvanic belt a series of cells connected to a sheath by means of the elastic connection B and the reversible insulated and noninsulated link D', substantially 115 as and for the purpose specified.

In testimony that I claim the above I have hereunto subscribed my name in the presence of two witnesses.

SAMUEL J. SPALDING.
